WINDOW LATCH

Filed Dec. 7, 1925

Attorney

UNITED STATES PATENT OFFICE

ARCHER L. KNAPP, OF DETROIT, MICHIGAN, ASSIGNOR TO PACKARD MOTOR CAR COMPANY, OF DETROIT, MICHIGAN, A CORPORATION OF MICHIGAN

WINDOW LATCH

Application filed December 7, 1925. Serial No. 73,587.

This invention relates to motor vehicles and particularly to window latching means therefor.

One of the objects of the invention is to 5 provide a simple latching means for the sliding windows of a motor vehicle body.

Another object of the invention is to provide an efficient latching device for simultaneously latching two sliding windows of 10 a motor vehicle.

Other objects and advantages of the invention will appear from the following description taken in connection with the drawing, which forms a part of this specification, 15 and in which:

Fig. 1 is an interior view of a motor vehicle body embodying the invention;

Fig. 2 is an enlarged elevation of a portion 20 of the vehicle body frame and two of the sliding windows of the body;

Fig. 3 is a vertical section substantially on the line 3—3 of Fig. 2;

Fig. 4 is a view similar to Fig. 3 with the locking bolt in unlatching position, and 25 Fig. 5 is a horizontal section on the line 5—5 of Fig. 2.

Referring to the drawing, 10 represents a partition between the front and rear compartments of a motor vehicle body and 11 30 and 12 are the two sliding windows arranged in an opening in said partition. In Fig. 3 the partition 10 is shown as formed with a horizontal longitudinal runway 13 in which the sliding windows 11 and 12 are arranged 35 to slide side by side. In all of the views these windows are shown in their closed position, that is, the position in which the windows entirely fill the opening between the front and rear compartments. The window 40 11 may be moved in the runway 13 so that it entirely overlaps the window 12 and thereby opens one-half of the space between the compartments. Or, both windows may be moved to the other side of the vehicle body so that 45 the other half of the space is open.

The lower part of each window has a suitable sash 14, secured to it in any desired way, as by cementing the window in a groove in the sash, and the adjacent vertical edges of 50 the windows have sash pieces 15 cemented

or otherwise secured to the glass. These sash pieces 15 have handles 16 thereon by which the windows may be moved from one position to another. The glass of each window is preferably notched or cut away at the lower inner corner as shown at 17, and when the windows are in their closed position these notches 17 are in alignment or may be said to register with each other. This may be particularly observed in Fig. 2. For the purpose of protecting the glass at the corner, a metal strip 18 is provided and adapted to fit the notch 17. This metal strip may be welded or otherwise secured to the sash 15 to thereby retain it in place.

A latching bolt is provided for locking both of the windows in their closed position, and in the form shown this is a U-shaped bolt 19 having an arm 20 for each of the windows 11 and 12. A spring 21 yieldingly retracts the bolt 19 and normally holds it in the position shown in Fig. 4. When the bolt is moved into its latching position as shown in Figs. 2 and 3, the latching arms 20 extend into the notches 17 and thereby prevent movement of the windows 11 and 12.

The latching bolt 19 is moved from its retracted position to its latching position by a hand operated device shown in the form of a shaft 22 having a handle 23 for operating it, and a cam 24 mounted on the shaft beneath the latching bolt 19. Stops 25 and 26 limit the movement of the cam. As shown, the stops 25 and 26 are so positioned that when the cam is moved to engage the latch bolt with the notches in the windows the cam is stopped at the point of its greatest travel with its nose immediately beneath the latch bolt and when the movement of the cam is reversed the cam is again stopped at the point of its smallest travel with its heel immediately beneath the latch bolt, thus the position of the latch bolt is determined by the position of the handle actuating the cam.

In Fig. 4 the latching bolt is in its unlatched position and the stop 26 is against the bolt 19. In Figs. 2 and 3 the latching bolt is in its latched position and the stop 25 is against the bolt 19. This is the dead center position of the cam and consequently the re-

tracting spring 21 cannot operate to move the bolt to its unlatched position.

While I have herein described in some detail a specific embodiment of my invention, which I deemed to be new and advantageous and may specifically claim, I do not desire it to be understood that my invention is limited to the exact details of the construction, as it will be apparent that changes may be made therein without departing from the spirit or scope of my invention.

Having thus described my invention, what I claim and desire to secure by Letters Patent is:

In combination, a runway, a pair of windows slideable therein, said windows having notches adapted to register, a floating reciprocatory U-shaped latch bolt positioned in the runway, a spring between the bolt and the runway intermediate the arms of the bolt, a cam engaging the bolt by line contact between the arms thereof, means actuating the cam to engage the notches and means limiting the travel of the cam so that movement thereof in one direction will be stopped when the nose of the cam engages the bolt and reverse movement of the cam will be stopped when the heel of the cam engages the bolt.

In testimony whereof I affix my signature.

ARCHER L. KNAPP.
